Elmer J. Ney of Lowell Mass.
Assignor to Lowell Manuf Company
Letter Patent No 1356 Date Dec 18 1860

The subscriber refers to the Letter Patent of the 18th day of December 1860, in which it is stated whom it may concern:

Be it known that I, Elmer J. Ney of Lowell, in the County of Middlesex and State of Massachusetts, have invented and designed a new Pattern for Carpets or other fabrics of which the following is a full, clear, and exact description, referring to the accompanying accompanying drawings, making part of this specification.

The principal pattern of this design, are the cross figures A, A & B B and the star shaped figures C, lying between figs A & B, and connected with them by small figures in the shape of a cross. The remainder of the design is occupied by small work D. The colors employed for the different portions of the design may be varied to suit the taste and wish of the manufacturer.

Claims
What I claim as my invention, and desire to secure by Letter Patent, is:-

The Design or Pattern for carpets or other fabrics herein set forth.
